METHOD AND APPARATUS FOR MAKING
REINFORCED TAPE

George Ellwood Houghton, Somerville, N. J., assignor to Johns-Manville Corporation, New York, N. Y., a corporation of New York

Application October 30, 1937, Serial No. 171,829

7 Claims. (Cl. 154—29)

This invention relates to a method and apparatus for making reinforced tape. More particularly, it relates to a method of making a reinforced tape in which the outer covering is formed of material comprising asbestos fibres and the inner reinforcing material is formed of paper or other suitable strengthening materials, and to a machine for simultaneously folding the outer covering and inserting the inner reinforcing material between the folds of the outer covering.

5 of material comprising asbestos fibres and the inner reinforcing material is formed of paper or other suitable strengthening materials, and to a machine for simultaneously folding the outer covering and inserting the inner reinforcing material between the folds of the outer covering.

It is an object of the present invention to provide a method and apparatus for making a reinforced tape which is compact and sufficiently strong to be handled during manufacture and 15 shipment as well as while being used in intended manner without becoming damaged.

Other objects and advantages, if not specifically pointed out, will be apparent to those skilled in the art from the following detailed description 20 of what is now considered the preferred embodiment of the invention.

In the drawings:

Fig. 1 is a top plan view of a folding device formed in accordance with the present invention; 25 Fig. 2 is a side elevational view of the device illustrated in Fig. 1;

Fig. 3 is a vertical sectional view taken substantially on the plane indicated by the line 3—3 in Fig. 1, and looking in the direction of the arrows; 30 Fig. 4 is a vertical sectional view taken substantially on the plane indicated by line 4—4 of Fig. 3, and looking in the direction of the arrows; and

Fig. 5 is a perspective view, partly in section, 35 of a reinforced tape made in accordance with the present invention.

Referring now to the drawings, the folding device comprises a pair of suitable supports 10, each of which has connected thereto at its upper end a bifurcated member 12 which forms a side of a frame of a pressing or creasing device, which in the form described takes the form of a set of rolls 14 and 16. The lower roll 14 is carried by a shaft 18 which is journaled directly at its ends in the plate 12. The upper roll 16 is carried by a shaft 20 which is journaled at each end in a block 22, each of which is slidably in known manner between the furcations 24 of a plate 12. A cross piece 26 extends across the top of and is suitably connected to the furcations 24 of each plate 12 and has a feed screw 28 threaded therethrough. Each feed screw is provided with a hand wheel 30 at its upper end and bears upon a follower plate 32 at its lower end. Interposed between each follower plate 32 and its respective block 22 is a compression spring 34. It will be seen that the degree of pressure exerted between the rolls 14 and 16 can be accurately controlled by rotating the hand wheel 30 at each end of the rolls to compress the springs 34 to the amount desired.

A side plate 36 is suitably connected to one of the plates 12 at one end and is suitably connected to a support 37 at the opposite end (see Figs. 2 and 4).

A second side plate 38 is suitably connected at 5 one end to the other of the plates 12, but does not extend downwardly as far as the plate 36, as shown in Fig. 3.

A supporting and dividing plate 40 has a flange 41 bent downwardly or otherwise formed along 10 one side and is connected to the side plate 36 by means of bolts or screws passed through the flange 41 and the side plate 36. (See Fig. 4.) The supporting and guiding plate 40 is turned down at one end as shown at 42 in Fig. 2 for a 15 purpose later to be described. It will be noted that there is sufficient clearance between the bottom of plate 38 and the top of plate 40 to provide for the passage of web material 68, as shown in Fig. 4.

20 A shaft 44 is journaled in the plates 36 and 38 and carries a roller 46 for rotation therewith between the plates 36 and 38. The shaft 44 is driven by means of a pulley 48 which is suitably driven by a belt or chain 49 from any well-known 25 type of prime mover. The shaft 44 is provided at its opposite end with a gear 50 which meshes with a gear 52 carried by the shaft 18 of the lower presser roll 14. Thus the roller 46 and roll 14 are driven together, and the diameters of the 30 roller and roll and the gears 50 and 52 are selected so that the roller 46 and roll 14 will have substantially the same peripheral speeds.

A shaft 54 is journaled at its ends in blocks 56 which are slidably mounted in known manner in 35 slots 58 formed in the plates 36 and 38. A roller 60 is rotatably mounted on the shaft 54 and an endless belt 62 is carried by the rollers 46 and 60. Lugs 64, which are turned out from the sides of plates 36 and 38 during the formation of the 40 slots 58, are threaded to receive set screws 66 which bear against the blocks 56 and thus provide means for adjusting the tension on belt 62.

A plow member 70 is suitably connected, as by means of screws 71, to the side of plate 38 and 45 extends downwardly and under the plate 40 as shown at 72.

The web material 68 is fed from any suitable conveyor 74 onto a guide chute 76. The guide chute 76 may take many different forms and 50 serves merely to direct the web material 68 onto the supporting and dividing plate 40. In the present instance it is shown as being supported by the side plate 36 through the intermediary of suitable connectors 78.

55 Rolls of reinforcing material 80 are rotatably mounted on a stud 82 carried by the support 37. Strips of reinforcing material 84, which may be paper, cloth, etc., pass from the supply rolls and over a guide 86 and under a guide 87 and then 60

onto the plate 40 at the turned down portion 42. The guides 86 and 87 have reduced portions 88 to receive the strips of reinforcing material 84 and are adjustably carried in slots 90 and 92 in the plate 36 through which these members project and are held in adjusted position by lock nuts 94 and 96, respectively.

A receiving chute 98 is connected to the side plates 12 of the pressing device through the medium of suitable fasteners 100 for the purpose of receiving the finished tape as it leaves the pressing device.

Operation of the device

15. As the web material 68 passes from the guide chute 76 onto the guiding and supporting plate 40, it is contacted by the belt 62 and held in contact with the plate 40 while it is moved therealong by the belt. The strips of reinforcing material 84 are simultaneously passed onto the plate 40 and between the plate and the web material 68. As shown in Figs. 1 and 4, the web material 68 is approximately twice as wide as the guiding and supporting plate 40, thus causing approximately half of the web material to extend over the plate 40 as shown at 102. As the web material 68 is advanced by the belt 62 the extending or overhanging portion 102 comes into contact with the plow 70 and is folded down and under the dividing and supporting plate 40. Thus a lower fold 104 and an upper fold 106 are formed and the folds are pressed together and creased along the fold as the tape passes between rolls 14 and 16. During the pressing and creasing operation the strips of reinforcing paper 84 are grasped by the folds 104 and 106 of the web material and secured in place, thus forming a reinforced tape comprising upper and lower folds and interior reinforcing strips.

40. By the use of the folding device just disclosed, a web material which is relatively delicate and hard to handle, such as material formed solely of loosely felted asbestos fibres or of a mixture of asbestos and other fibres, can be associated with stronger reinforcing material, such as strips of paper 84, and a relatively strong and compact reinforced tape thus formed.

The foregoing details have been given for the purpose of explanation and not limitation since 50 many changes and modifications may be made in the actual structure disclosed without departing from the spirit of the invention.

The invention having been described, what I claim is:

55. 1. A reinforced-tape forming device comprising a supporting and dividing plate, means for feeding web material onto said plate with a part of said web material extending from a side of said plate, means for holding said web material in contact with said plate and for advancing the material therealong, means for feeding reinforcing material between said plate and web material, and a plow for folding said extending part of said web material under said plate as the web material is advanced therealong.

2. A reinforced-tape forming device comprising a supporting and dividing plate, means for feeding web material onto said plate with a part of said web material extending from a side of said plate, means for holding said web material in contact with said plate and for advancing the material therealong, means for feeding reinforcing material between said plate and web material, a plow for folding said extending part

of the web material under said plate as the web material is advanced therealong, and pressure applying means for creasing the web material along the fold to secure the folded web material and reinforcing material together to form a reinforced tape. 5

3. A reinforced-tape forming device comprising a supporting and dividing plate, means for feeding web material onto said plate with a part of said web material extending from a side of said plate, belt means for holding said material in contact with said plate and for advancing the material therealong, means for feeding strips of reinforcing material between said plate and web material, a plow for folding said extending part of the web material under said plate as the web material is advanced therealong, and pressure applying means for receiving said web and reinforcing materials and creasing the web material along the fold to form a reinforced tape. 10 20

4. A reinforced tape forming device comprising a dividing member, means for feeding web material into contact with said member with a part of said web material extending from a side of said member, means for holding said web material in contact with said member and for advancing the material therealong, means for feeding reinforcing material into contact with said member, and means for folding said extending part of said web material around said member as the web material is advanced therealong. 25 30

5. A reinforced tape forming device comprising a dividing plate, means for feeding web material into contact with said plate with a part of said web material extending from a side of said plate, 35 means for holding said web material in contact with said plate and for advancing the material therealong, means for feeding reinforcing material between said plate and web material, means for folding said extending part of said web material around said plate as the web material is advanced therealong, and pressure applying means for creasing the web material along the fold to secure the folded web material and reinforcing material together and to form a reinforced tape. 40 45

6. The method of forming a tape from a loosely felted fibrous web material and a reinforcing material, comprising feeding said web material onto a dividing member with a part of said web material extending from a side thereof, advancing the web material, feeding reinforcing material to a surface of said web material, folding the extending part of said web material in lapping relationship to said dividing member and 55 web material thereon, removing said web material from said dividing member and pressing the web material along the fold to secure the lapped portions of said web material with the reinforcing material embraced therebetween. 00

7. The method of forming a tape from a loosely felted fibrous web material and a reinforcing material, comprising advancing and supporting the web material over approximately one half its width to form a supported portion and an unsupported extending portion, feeding the reinforcing material to a surface of said web material and folding the unsupported portion of said web material into lapping relationship to the supported portion thereof and in such a 70 manner that the reinforcing material lies between said lapping portions, and pressing the web material along the fold.

GEORGE ELLWOOD HOUGHTON.
